JUG

Paul A. Marchant, Kansas City, Mo., assignor to Rexall
Drug and Chemical Company, Los Angeles, Calif., a
corporation of Delaware

Filed Sept. 18, 1964, Ser. No. 82,043

Term of patent 14 years

(Cl. D58—5)

FIG. 1

FIG. 2

FIG. 3

FIG. 4

FIG. 5

FIG. 6

FIG. 7

FIG. 8

FIG. 1 is a side elevation view of the jug showing my new design.

FIG. 2 is a side elevation view thereof with the jug rotated 90° from the position shown in FIG. 1.

FIG. 3 is a top plan view thereof.

FIG. 4 is the cross section taken on line 4—4 of FIG. 1.

FIG. 5 is a fragmentary view of the upper portion of a jug showing a modified form of my new design.

FIG. 6 is a side elevation thereof, partly in cross section, with the jug rotated 90° from the position shown in FIG. 5.

FIG. 7 is a side elevation view of a jug showing a second modified form of my new design, and.

FIG. 8 is a side elevation view thereof, partly in cross section, with the jug rotated 90° from the position shown in FIG. 7.

The dominant features of my design reside in the configuration of the finished neck in combination with the handle wherein the handle is connected to the collar, all as shown.

The lower portion of the jugs shown in FIG. 5 through 8 inclusive is identical to the lower portion of the jug shown in FIGS. 1 and 2.

This application is a continuation in part of my earlier application Serial Number D. 72,618, filed November 27, 1962, and now abandoned.

I claim:

The ornamental design for a jug, as shown and described.
